UNITED STATES PATENT OFFICE

172,339

DISPLAY BOARD

David R. Cummins, Ridgewood, N. J.

Application January 4, 1954, Serial No. 28,348

Term of patent 7 years

(Cl. D1—2)

To all whom it may concern:

Be it known that I, David R. Cummins, have invented a new, original, and ornamental Design for a Display Board, or which the following is a specification, reference being had to the accompanying drawing, forming a part hereof. In the drawing:

Fig. 1 is a view in perspective of a display board showing my new design.

Fig. 2 is a view in side elevation of the display board.

I claim:

The ornamental design for a display board, substantially as shown.
